UNITED STATES PATENT OFFICE.

ROBERT MARTIN MAYES, OF SAN ANTONIO, TEXAS.

DENTAL HANDPIECE.

No. 911,510.

Specification of Letters Patent.

Patented Feb. 2, 1909.

Application filed July 3, 1908. Serial No. 441,854.

To all whom it may concern:

Be it known that I, ROBERT MARTIN MAYES, a citizen of the United States, residing at San Antonio, in the county of Bexar and State of Texas, have invented a new and useful Dental Handpiece, of which the following is a specification.

This invention relates to dental engine hand pieces; and has for its object to provide a simple, accurate and convenient hand-piece for holding dental tools for straight line work, and for attaching thereto an angle piece by means of which said tools may be held and rotated at an angle to the hand piece.

With this and other objects in view the invention consists of the construction, combination and arrangement of parts herein-after described and claimed, and illustrated in the accompanying drawing in which:—

Figure 1 is a side view of the hand piece with a right angle tool holder connected thereto; Fig. 2 a longitudinal sectional view of the same; Fig. 3 a similar sectional view of a portion of the hand piece with the right angle holder removed and a tool held thereby for straight work; Figs. 4 and 5 perspective views of detail parts of the invention, and Fig. 6 is a detail sectional view of the angle piece.

Similar reference numerals are used for the same parts in all the figures.

In the drawing, 1 represents the casing or barrel of the hand piece having a slight conical taper, exteriorly, from its rear end to its tip and, near its rear a circumferential rib or bead 2, preferably knurled, as shown. The casing 1 is bored longitudinally through its length for a spindle 3, the rear end being counter bored as far as the rib or bead 2 to form a socket, producing thereby a shoulder or seat 4. The tip end is also counter bored for a short distance and threaded throughout its length; the socket is threaded internally for a short distance only.

Rotatably mounted in the bore of the casing 1 is the spindle 3 having a collar 5 near its rear end which abuts against the shoulder 4, and is prevented thereby from moving in a forward direction. The collar 5 is held against the shoulder, and a bearing provided for the rear end of the spindle 3 by a coupling 6 exteriorly threaded on one end 7 to screw into the threaded socket in the barrel and bear against the rear end of the collar 5. The coupling 6 has a central bore through

which the rear end of the spindle 3 extends and in which it has a bearing. The rear end 9 of the coupling 6 is counter-bored and interiorly threaded for the end of the sheathing 10 which covers the ordinary flexible driving shaft 13 soldered in an axial hole in the rear end 8 of the spindle 3.

The forward end 11 of the spindle 3 is formed into a tool holder in which may be secured the shank of the bur or drill 25 for straight work or the shaft 14 of an angle piece 12. Inwardly from its end 11 a central longitudinal bore 15 is made in the spindle for a sufficient distance and of such diameter as to permit the shaft of an angle piece, a drill, or other tool to slide freely therein without side play. A transverse slot 18 is cut across the tool holder at the end of the bore 15 from one side thereof inwardly to its center, the bottom of said slot being flat and in a plane passing through the axis of said bore. One-half the bore 15 is therefore open to the slot 18 so that when a drill or other tool or a shaft with its end flattened is inserted in the bore with its flat side bearing on the bottom of the slot, the rotation of the spindle will necessarily cause the tool to rotate with it.

When the angle piece 12 is to be attached to the hand piece a nozzle 19 having a threaded stud 20 is screwed into the forward end of the casing 1, said stud 20 being bored out to form a socket 21 for the forward end of the spindle 3. The nozzle 19 is reduced or coned towards the angle piece and is provided with an outwardly projecting stem 22 threaded for about one-half its length, the outer end being smooth. On this stem 22 the angle piece 12 is screwed as shown in Fig. 1. A bore of suitable size is formed in the nozzle in which the shaft 14 of the angle piece is mounted. For straight work, the nozzle 19 is removed, and a cap piece 23 substituted therefor, the stem 24 of which is not threaded. A tool 25 with its shank end 26 flattened and slightly bent or curved towards the flattened side is placed in the bore spindle 3 so that its flattened side will engage the bottom of the slot 18. The end of the tool shank being bent towards the flattened side will strike the inclined end 27 of the bore and be forced upwardly so that it can enter the slot 18. The tool shank being elastic bears on the bottom of the slot 18 with sufficient friction to hold it in place and prevent it from being withdrawn with-

out exercising more force than would be encountered in the work it has to do.

The angle piece is attached by first withdrawing the tool and unscrewing the cap piece 23, then the angle piece 12 with the coupling 23 screwed thereto and the shaft 14 projecting beyond the coupling is screwed in position on the hand piece by first inserting the end of the shaft into the spindle 5 until 10 its flattened inclined end engages the bottom of the slot 18.

The operation of the instrument is apparent from the above description. End-wise movement of the spindle is prevented 15 by the collar 5 thereon bearing against the shoulder 4 and the end 7 of the coupling 6.

What is claimed is:—

1. In a dental hand-piece, the combination with an outer casing, of a rotatable 20 spindle mounted in the casing and having a central longitudinal bore in its forward end, a transverse slot extending from its periphery to its axis at the base of said bore and having a flat bottom and an inclined surface 25 extending from the bottom of the bore to the bottom of the slot.

2. In a dental hand-piece, the combination with an outer casing, of a spindle mounted to rotate axially in said casing and 30 having a central longitudinal bore in its forward end, a transverse slot extending from its periphery to its axis at the base of said bore and having a flat bottom and an inclined surface extending from the bottom of the bore to the 35 bottom of the slot and adapted to receive a tool-shank having a flattened side on its rear end, said rear end being deflected slightly towards said flattened side.

3. In a dental hand-piece, the combination with an outer casing having a central longitudinal bore counter bored at each end, 40 a rotatable spindle fitting said bore and having a collar fitting the rear counter bore, means for retaining said collar and spindle in place, said spindle provided with a tool-holder on its forward end comprising a longitudinal bore for a tool, and a transverse slot intersecting said bore in a plane passing through its axis to form a plane surface for a tool to bear on and to be rotated with the spindle, of a nozzle having a spindle bearing within the casing, a projection in line therewith on its outer end, and a bore extending through the nozzle in line 45 with the bore in the spindle. 50

4. In a dental hand-piece, the combination with a casing, a spindle rotatably mounted in the casing and having a tool-holder on its forward end, of a nozzle having a threaded extension adapted to screw into the forward end of the casing and provided with a bearing seat on its inner side 60 for the end of said spindle and a partly threaded stem projecting forwardly from 65 the center of said nozzle on which an angle piece is adapted to screw, said nozzle having a central bore in line with said tool-holder to receive the driving shaft of said angle-piece as it is pushed into the tool-holder. 70

In testimony that I claim the foregoing as my own, I have hereto affixed my signature in the presence of two witnesses.

ROBERT MARTIN MAYES.
